WILLIAM C. ROE, OF ELYRIA, OHIO, ASSIGNOR TO TELKOR, INC., OF ELYRIA, OHIO, A CORPORATION OF OHIO

SCREW DRIVER

Application filed October 2, 1929. Serial No. 396,688.

My invention relates to improvements in screw drivers and relates more particularly to a screw driver of the so-called ratchet type.

An object of my invention is to provide a ratchet screw driver wherein the ratchet mechanism is entirely enclosed in a housing.

Another object of my invention is to provide an improved ratchet screw driver which may be adjusted to drive screws clockwise or counter-clockwise.

Another object of my invention is to provide a screw driver wherein the ratchet mechanism may be readily reversed without operating extraneous levers or pawls.

Another object of my invention is to provide a screw driver wherein the ratchet mechanism may be reversed by pulling out on the bit and turning in one half a turn in either direction.

Another object of my invention is to provide a ratchet screw driver wherein the ratchet mechanism is simple and compact, having few working parts.

Other objects of my invention and the invention itself will become apparent from the following description of an embodiment of my invention in which description reference will be had to the accompanying drawings forming a part of this specification.

Referring to the drawings:

Fig. 1 is an elevational view of my invention;

Fig. 2 is a vertical medial sectional view of my invention, certain parts being shown in fragmentary elevation.

Figs. 3, 4 and 5 are end, side elevational and perspective views of ratchet ends of the handle.

Figs. 6, 7, 8 and 9 are top plan, side, bottom plan and vertical medial sectional views of a floating clutch used in my invention.

Figs. 10 and 11 are fragmentary elevational views of the ratchet clutch control rotated through 90° relative to each other.

Referring now to the figures of the drawings wherein like parts are designated by like reference characters, my screw driver comprises generally a handle 1, ratchet housing 2 and bit 3.

As best illustrated in Fig. 2, a central bore

4 extends nearly through the handle and a ferrule 5 is disposed about the lower end. A sleeve 6 is telescoped in the bore of the handle and is provided with an enlarged annular end 7.

The end or face 8 of the sleeve is provided with three downwardly extending equally spaced lugs 9, disposed radially about the bore 10 of the sleeve. The housing 2 is telescoped over the annular end 7 and is secured thereto by a screw 11 which is passed through a countersunk hole in the housing into the threaded end 7.

The housing is provided with an enlarged bore 15 adjacent the upper end, adapted to house the floating clutch or dog 16, and a lower smaller bore 17 into which a control element 18, which is secured to the shaft of the bit, is adapted to telescope.

The floating clutch element comprises a relatively short cylinder having a tapered central bore 19. The lower end surface 20 is provided with transverse notches 21 and 21', and the opposite upper end 22 is provided with two ratchet teeth 23 and 24, which face in opposite directions. Between the ratchet teeth 23 and 24 are provided two elevated rocking edges 40—40 for a purpose to be described.

The periphery of the cylinder is provided with two grooves 26 and 27 parallel to the faces 25 of the teeth which support a resilient steel clip 28, so as to provide a pair of loops 29 and 30.

The bit 3 is adapted to telescope into the handle through the clutch element and sleeve, and is provided with a clutch adjusting control 18, which is generally cylindrical in the lower portion 31 and is provided with an annular flange 32 adjacent the upper end, which supports an upwardly extending boss 33 having a slanting upper surface 34 adapted to be lodged in one of the notches 21 or 21'.

The cylindrical portion extends through the apertured end 35 of the housing. A helical compression spring 36 is disposed around the cylindrical portion one end thereof abutting against the end wall of the housing and the other end exerting pressure on the flange 100

32 to resiliently force the bit upward into the housing.

The effect of the pressure of the spring on the bit, when the boss 33 on the flange 32 is disposed in the notch 21, is to cause the clutch element to be tilted. This is made possible by the tapered bore, and the fact that the tooth 23 (or 24) can be displaced axially in one of the intervening spaces between the lugs 9. The tilting of the clutch element is rendered positive by having the rocking edges 40—40 positioned between the notches 21 and 21', whereby when the boss 33 presses upwardly in one or the other of the notches 21 or 21', one of the rocking edges 40—40 will abut upon one of the lugs 9 and the clutch element as a whole will rock on the said edge to cause the tooth 23 or 24 to enter a space between the lugs 9.

20 When the handle is rotated clockwise or to the right, as viewed in Fig. 2, the tooth 23, which is disposed above the notch 21, the clutch element being tilted by the lug or cam 33 in the notch 21, is engaged by one of the projecting lugs 9 on the end of the handle, and is rotated thereby, which rotation is communicated to the bit through the notch 21 and cam 33. The lugs 9 at this time clear the tooth 24, the latter being depressed due to the rocked or tilted position of the clutch element.

When the handle is rotated counter-clockwise, the slanting surface 23' of the tooth 23, engages the lugs 9, allowing the lugs to ride over the teeth and the bit is not rotated.

With the screw driver adjusted as illustrated in Fig. 2, it is adapted to screw the ordinary right hand thread screw or bolt, and the ratchet is operative when turned to the left.

When it is desired to reverse the mechanism in order that it may operate the bit to the left and ratchet to the right, the bit is pulled downward and turned one half turn, or 180° to either the right or left.

50 The spring loops 29 and 30 of the clutch element are adapted to bear against the walls of the bore to retain the clutch element in a so-called floating position. When the bit is pulled down against the pressure of the spring 36, the annulus 32 and lug or cam 33 are telescoped into the smaller bore out of contact with the clutch element, and may be rotated to either the right or left without affecting the clutch element.

When the bit is rotated 180° and then released the lug or cam 33 enters the notch 21' disposed opposite the notch 21 and tilts the clutch element in the opposite direction, so that the tooth 24, which faces in the opposite direction to the tooth 23, is engaged by the lugs 9, and the ratchet is thus reversed, the lugs 9 now clearing or passing over the tooth 23.

60 65 When rotated to the right, the back or

70 slanting surface of the tooth 24 engages the lugs 9 and they slip over it; when rotated to the left the face of the tooth 24 engages the lugs and movement is transmitted through the notch 21' to the cam or lug 33, and thence to the bit.

Having thus described my invention in a preferred embodiment, I am aware that numerous and extensive departures may be made from the embodiment herein illustrated and described, but without departing from the spirit of my invention.
